UNITED STATES PATENT OFFICE.

ADAM P. THOMASSON, OF CHICAGO, ILLINOIS.

FUEL-SAVING DEVICE.

1,396,472.

Specification of Letters Patent.

Patented Nov. 8, 1921.

Application filed April 2, 1921. Serial No. 457,909.

To all whom it may concern:

Be it known that I, ADAM P. THOMASSON, a citizen of the United States, and a resident of the city of Chicago, county of Cook, and 5 State of Illinois, have invented certain new and useful Improvements in Fuel-Saving Devices, of which the following is a specification.

My invention relates to improvements in 10 fuel saving devices, and has for its principal object the provision of an improved construction of this character which will be highly efficient in use.

A further object of my invention is the 15 provision of a heating device whereby ashes containing cinders and unburned particles of combustion or the like can be consumed.

Other objects will appear hereinafter.

The invention consists in the combinations 20 and arrangements of parts hereinafter described and claimed.

The invention will be best understood by 25 reference to the accompanying drawing forming a part of this application, and in which,

Figure 1 is an elevational view of a heating apparatus partly in section, showing my improved construction mounted thereon; and

Fig. 2 is a sectional view of the same taken 30 substantially on line 2—2 of Fig. 1.

The preferred form of construction, as 35 illustrated in the drawing, comprises a heating apparatus 4 of any construction or design, having the usual grate 5. A rod 6 is centrally rotatably mounted on the heating apparatus 4, directly over the fire bed 7. One end of the rod 6 is provided with a 40 handle 8 to afford a means for manual operation. Rigidly fixed to the rod 6 is a metallic plate 9 semi-circular in shape and arranged to serve as a check, changing the course of the draft through the grate. A metallic supply pipe 10, having a plurality

45 of perforations and controlled by a hand valve 10', is mounted directly over a bed of ashes 11 which are to be consumed, and arranged to constantly moisten the ashes when desired. Directly opposite the fire door 50 12, another fire door 12' is hingedly mounted on the heating apparatus, providing an opening through which the ashes are fed to the ash bed 11. The metallic plate 9 is provided with a depending flange 9' arranged

55 to prevent the ashes from being thrown onto

the front portion of the fire as the said ashes are fed through the door 12'.

In operation, a fire is built in the combustion chamber in the usual manner, providing two individual fire beds 7, one-half 60 of which is arranged to receive fresh fuel and the other half arranged to receive ashes or the like. The hand valve 10' is then opened, allowing the desired amount of water to flow onto the bed of burning ashes 65 containing cinders and unburned particles of combustion, causing the same to discharge an inflammable gas, transforming the ashes containing cinders and unburned particles of combustion into a soft lumpy 70 form which will be readily consumed. The plate 9 is swung into a vertical position until the fire is properly burning, at which time the plate 9 is swung back closing the front half of the combustion chamber, 75 changing the course of the draft and causing the products of combustion to pass through the bed of ashes, thereby keeping the bottom of the ashes burning. During the progress of combustion should the ashes 80 or the like cause the fresh fuel to become partly extinguished, the plate 9 can be swung over covering the bed of ashes and causing the draft to change its course, passing directly through the bed of fresh fuel. 85 By my arrangement, a simple and inexpensive fuel saving device can be installed in any stove, furnace or the like, and ashes, garbage, paper or the like can be consumed without quenching the bed of burning fuel. 90

While I have illustrated and described the preferred form of construction for carrying my invention into effect, this is capable of variation and modification without departing from the spirit of the invention. I, therefore, 95 do not wish to be limited to the precise details of the construction set forth, but desire to avail myself of such variations and modifications as come within the scope of the appended claims.

Having described my invention, what I 100 claim as new and desire to secure by Letters Patent, is

1. In combination with a heating apparatus having a grate and oppositely arranged doors; a supporting member rotatably mounted in the combustion chamber of said heating apparatus; a draft shield having a depending flange formed on said member and operative therewith; and a handle 105

110

formed on said supporting member for manipulating said shield over opposite portions of said grate, substantially as described.

- 5 2. In combination with a heating apparatus having a grate and oppositely arranged doors; a rod rotatably mounted in the combustion chamber of said heating apparatus; a draft shield formed from a single 10 piece of material mounted on said rod and operative therewith; a depending flange formed on said shield; and a handle integrally formed on said rod for manipulating said shield over opposite portions of said 15 grate.
3. In combination with a heating apparatus having a fire grate and combustion chamber; means for feeding fresh fuel to one portion of said grate; means for feeding moist ashes containing unburned particles 20 of combustion to the other portion of said grate; a rod rotatably mounted in said combustion chamber; a plate mounted on said rod and operative therewith; a depending 25 flange on said plate for preventing said ashes from being fed on said first-mentioned

portion of said grate; and a handle on said rod for rotating said plate over one portion of said grate to the other portion of said 30 grate, substantially as described.

4. In combination with a heating apparatus having a fire grate and combustion chamber; means for feeding fresh fuel to one portion of said grate; means for feeding moist ashes containing unburned particles 35 of combustion to the other portion of said grate; and a draft shield rotatably mounted in said combustion chamber arranged to be shifted over opposite portions of said grate, one end of said shield being bent downwardly substantially at right angles for preventing said ashes from being fed on said 40 first-mentioned portion of said grate, substantially as described.

In testimony whereof I have signed my 45 name to this specification in the presence of two subscribing witnesses.

ADAM P. THOMASSON.
